[57] **CLAIM**

The ornamental design for a window glass for motor vehicle, as shown and described.

DESCRIPTION

FIG. 1 is a front elevational view of a window glass for motor vehicle showing our new design;

FIG. 2 is a rear elevational view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is an enlarged fragmentary front elevation view thereof of the portion within the circled area 7 in FIG. 1.

The characteristic feature of my design resides in the multi-trapezoidal shaped VHF antenna within the window glass as best illustrated in FIGS. 1 and 2 in the drawing.

FIG. 1

FIG. 2
